CONTAINER FOR FOODSTUFFS

Gerald E. Mider, 783 Wiltshire Road,
Columbus, Ohio 43204

Filed Sept. 23, 1971, Ser. No. 183,303

Term of patent 14 years

Int. Cl. D7—01

U.S. Cl. D44—1 B

FIG. 1

FIG. 2

FIG. 3

FIG. 4

FIG. 5

FIG. 1 is a top plan view of a container for foodstuffs showing my new design;

FIG. 2 is a side elevational view thereof;

FIG. 3 is a sectional view taken along the line 3—3 in FIG. 1;

FIG. 4 is a fragmentary sectional view on an enlarged scale taken on line 4—4 in FIG. 1; and

FIG. 5 is a fragmentary sectional view on an enlarged scale taken on line 5—5 in FIG. 2.

I claim:

The ornamental design for a container for foodstuffs, as shown.
